UNITED STATES PATENT OFFICE.

ALEXANDER S. TRAUB, OF YONKERS, NEW YORK.

SAFETY APPLIANCE FOR HATCHWAYS.

1,200,050.

Specification of Letters Patent.

Patented Oct. 3, 1916.

Application filed December 24, 1915. Serial No. 68,466.

To all whom it may concern:

Be it known that I, ALEXANDER S. TRAUB, a citizen of the United States, and a resident of Yonkers, county of Westchester, and 5 State of New York, have invented certain new and useful Improvements in Safety Appliances for Hatchways, of which the following is a specification.

My invention is designed to safeguard elevator or hoist hatchways, especially those in which the bottom of the shaft consists of a portion of a hall or passageway constituting the entrance to a building, as frequently happens in the older constructions of warehouse and other buildings used for commercial purposes.

The main object is to afford an automatically closing and locking hatch-guard or trap door which can only be opened manually by a person in possession of a key to the release mechanism, so that the accidental or unobserved descent of the "lift" into the passageway is guarded against and rendered practically impossible, all as hereinafter 25 more fully set forth.

In the accompanying drawings, Figure 1, is a sectional elevation of the lower portion of a hatchway and parts adjacent thereto, showing my hatch guard closed; Fig. 2, is 30 a similar view showing the hatch guard open; Fig. 3, is a horizontal section taken upon plane of line 3—3, Fig. 1; Fig. 4, is a sectional elevation upon a larger scale of the locking and releasing mechanism, illustrating the locking of the hatch guard in its closed, horizontal position; Fig. 5, is a section taken upon planes of line 5—5, Fig. 4; Fig. 6, a view similar to Fig. 4, showing the locking of the hatch guard in its open 40 vertical position; Fig. 7, is a section taken upon plane of line 7—7, Fig. 6; Fig. 8, shows in detail a means of automatically locking the parts in closed relationship.

A, represents a passage way, say, on the 45 ground floor of a commercial or warehouse, or similar situation, B, representing an elevator or hoist shaft, the lower portion of which terminates in said passage way.

A', A², represent floors or stories above 50 the passage way A. I herein show and describe my safety hatch apparatus as applied for the immediate protection of the passage way A, although it may obviously be duplicated for the hatch ways of floors 55 above if so desired.

C, represents symbolically a car, platform,

or hoist (the "lift") of any desired or well known construction, suspended upon a cable c, or equivalent, and raised and lowered in the shaft by well known means.

b, b', b², b³, are uprights positioned at the four corners of the shaft B, and represented in the drawings as made of angle iron.

The hatch guard G, is pivotally mounted, as at g, between the uprights b', b³, on one side of the shaft, and when lowered or closed rests against a sustaining bar or stop g', between the other two uprights b, b², or is otherwise supported in prescribed position to close the hatchway and protect the passage A. As shown herein the hatch guard is of rectangular grille form, although this is not essential; and it is provided by any suitable means with a counterweight w, 60 which partly compensates for the weight of the hatch guard G, although not fully so, the object being to allow the weight of the hatch guard G, to preponderate sufficiently to cause it to close automatically when released, while the counterweight w, facilitates the opening or raising of the hatch guard manually by means of the flexible connection g², pendant from the rear extension g³, of the hatch guard as shown more 70 particularly in Figs. 1, and 3.

The hatch guard G, is secured in horizontal position by means of a locking arm d', rigid upon the vertical rod or shaft d, which is fulcrumed in bearings b⁴, b⁴, on the upright 75 b³. The upper, horizontal edge d⁴, of the locking arm d', is bent inward so as to project under the hatch guard extension g³, when the said guard is in horizontal position as in Figs. 1, 3, 4, and 5,—a torsion 80 spring d⁵, attached at one end to the rock shaft d, and at the other to the upright b³, (as shown in Figs. 4, and 6,) tending constantly to thrust the locking arm d', inward either with its upper horizontal edge d⁴, 85 under the extension g³, of the hatch guard G, as aforesaid, or with its vertical edge d⁵¹, resting against said guard extension g³, or the lateral branch g⁴, thereof, as in Figs. 2, 6, and 7. It will thus be seen that 90 the function of the hatch guard extension g³, is twofold, in that it affords means for holding the hatch guard in horizontal position as well as for holding back the locking arm d', against the resistance of the 95 torsion spring d⁵, as soon as the hatch guard G is moved from its horizontal position.

The lower portion of the rock shaft d , is provided with a hand lever d^6 , by means of which said shaft and its locking arm d' , may be rocked back against the resistance 5 of the torsion spring d^5 , to release the hatch guard; and means are provided for positively securing the rock shaft against movement when the locking arm d' , is under the hatch guard extension g^3 , until released 10 manually. Obviously this may be accomplished by various well known mechanical expedients and I do not limit myself to the exact construction and arrangement of parts shown in the drawings, in which the rock 15 shaft d , is formed with a mortise d^x , for the reception of the outer end of the spring bolt s , of any suitable key lock mechanism, represented symbolically by S , in the drawings.

20 A trip latch T , pivotally supported on the upright b^8 , in alignment with the hatch guard extension g^3 , secures the hatch guard in its open or vertical position by engagement with the end of the extension g^3 , when 25 the "lift" C , is lowered as indicated in Fig. 6, in which c' , represents any contacting portion of the car C , and t , a retractile spring which normally holds the trip latch T , against a stop t' , (Fig. 4) when the car 30 is out of contact with said trip latch T .

The operation is as follows:—The parts being in the relative positions shown in Figs. 1, 3, 4, and 5, that is to say with the hatch guard G , lowered and positively held 35 in position across the shaft B , thereby protecting the passageway A , and it being desired to use the "lift" C , for the purpose of either raising or lowering goods or passengers from or to the ground floor or passage way A , it is requisite that a person 40 having the necessary key to the lock S , be present and in position to throw back the bolt s , which otherwise holds the rock shaft d , against axial movement, and in this connection it may be stated that a "Yale" or 45 any other form of key lock may be used for the purpose, the bolt being preferably of the spring latch or automatic locking type. The withdrawal of the bolt s , from the mortise 50 d^x , in the rock shaft d , admits of the rocking of said shaft d , by means of the handle d^6 , against the resistance of the torsion spring d^5 , thereby withdrawing the horizontal edge d^4 , of the locking arm d' , from 55 underneath the extension g^3 , of the hatch guard G , so that the latter may be raised into vertical position by means of the flexible connection g^2 , attached to said extension g^3 ,—the counterweight w , aiding in the 60 operation.

As soon as the hatch guard G , turning on its pivotal support g , is inclined from its horizontal position its extension g^3 , is opposed to the retracted vertical edge d^{51} , of 65 the locking arm d' , so that said extension

g^3 , and its lateral branch g^4 , will then hold back the locking arm d' , against the resistance of the retractile spring d^5 , which latter tends constantly to rock the shaft d , back into its original position,—the lateral branch g^4 , enabling the extension g^3 , to perform this function even when the hatch guard has assumed the vertical position shown in Figs. 2, 6, and 7.

The hatch guard G , is held in the vertical 75 position with its free edge g^5 , against a stop b^5 , as shown in Fig. 2, by means of the flexible connection g^2 , until the car or lift C , in its descent encounters and trips the latch T , thereby causing the latter to engage and hold the end of the extension g^3 , as shown in Fig. 6, so that the hatch guard G , will then be locked in open position as long as any portion (c') of the car remains 80 in contact with the latch T , so that the flexible connection g^2 , may be released under these conditions.

When in its ascent the car C , clears the trip latch T , the retractile spring t , will restore said latch to its normal position at rest 90 against the stop t' , as shown in Fig. 4. As the car ascends still farther it will prevent the closing of the hatch guard G , until the bottom of the car C , clears the free end g^5 , of said guard, when the preponderance of 95 weight of the guard G , over the counterweight w , will cause the guard G , to again and gradually assume the horizontal position with its free end g^5 , resting against the stop g' , as in Fig. 1,—the counterweight 100 w , rendering this automatic closure of the hatch guard G , less abrupt and forcible than the operation would otherwise be, and this is the main object of the provision of the counterweight w , as it is obvious that the 105 apparatus would be operative without it. Furthermore the counterweight if employed may obviously be applied to the hatch guard G , otherwise than in the identical manner shown herein, by resorting to 110 various mechanical expedients with like result, and without departing from the spirit and intent of my invention in this respect.

As soon as the hatch guard G , assumes its horizontal position the spring d^5 , rocks 115 the shaft d , back into its original position with its locking arm d' , under the extension g^3 , and the bolt s , springs into the mortise d^x , and thereby again locks the parts in the relative positions first described and shown 120 in Figs. 1, 3, 4, and 5, and again safeguarding and protecting the passageway A .

I have herein shown and described operative means for attaining the object of my invention, although I do not wish to limit 125 myself to minor details which may be varied with like result.

What I claim as my invention and desire to secure by Letters Patent is,

1. In safety appliances for hatchways of 130

- the character designated, the combination of a pivotally supported hatch guard formed with an extension beyond said pivotal support, a rock shaft formed with a locking arm adapted to protrude under said guard extension when the guard is in closed position and with means for effecting the rocking of said shaft, and key-actuated locking means for securing the said rock shaft in prescribed position for the purpose set forth. 5
2. In safety appliances for hatchways of the character designated, the combination of a pivotally supported and counterweighted hatch guard formed with an extension beyond said pivotal support, a rock shaft formed with a locking arm adapted to protrude under said guard extension when the guard is in closed position and with means for effecting the rocking of said shaft, and key-actuated locking means for securing the said rock shaft in prescribed position for the purpose set forth. 10
3. In safety appliances for hatchways of the character designated, the combination of a pivotally supported and counterweighted hatch guard formed with an extension beyond said pivotal support, a rock shaft formed with a locking arm adapted to protrude under said guard extension when the guard is in closed position and with means for effecting the rocking of said shaft, key-actuated locking means for securing the said rock shaft in prescribed position, and a retractile spring connected with said rock shaft and tending constantly to hold it in said prescribed position. 15
4. In safety appliances for hatchways of the character designated, the combination of a pivotally supported and counterweighted hatch guard formed with an extension beyond said pivotal support, a rock shaft formed with a locking arm adapted to protrude under said guard extension when the guard is in closed position and with means for effecting the rocking of said shaft, key-actuated locking means for securing the said rock shaft in prescribed position, and a retractile spring connected with said rock shaft and tending constantly to hold it in said prescribed position. 20
5. In safety appliances for hatchways of the character designated, the combination of a pivotally supported and counterweighted hatch guard formed with an extension beyond said pivotal support, a rock shaft formed with a locking arm adapted to protrude under said guard extension when the guard is in closed position and with means for effecting the rocking of said shaft, key-actuated locking means for securing the said rock shaft in prescribed position, a retractile spring connected with said rock shaft and tending constantly to hold it in said prescribed position, and a flexible connection attached to said rear extension of the hatch guard, for the purpose described. 25
6. In safety appliances for hatchways of the character designated, the combination of a pivotally supported and counterweighted hatch guard formed with an extension beyond said pivotal support, a rock shaft formed with a locking arm adapted to protrude under said guard extension when the guard is in closed position and with means for effecting the rocking of said shaft, key-actuated locking means for securing the said rock shaft in prescribed position, a retractile spring connected with said rock shaft and tending constantly to hold it in said prescribed position, and a trip latch actuated by the lift or car and adapted to lock the hatch guard in open position, as and for the purpose set forth. 30
7. In safety appliances for hatchways of the character designated, the combination of a pivotally supported and counterweighted hatch guard formed with an extension beyond said pivotal support, a rock shaft formed with a locking arm adapted to protrude under said guard extension when the guard is in closed position and with means for effecting the rocking of said shaft, key-actuated locking means for securing the said rock shaft in prescribed position, a retractile spring connected with said rock shaft and tending constantly to hold it in said prescribed position, and a trip latch actuated by the lift or car and adapted to lock the hatch guard in open position, as and for the purpose set forth. 35
